AUTOMATIC STOP DEVICE

Charles B. Fantone, Lyndhurst, and Reuben M. Jameson, Teaneck, N. J., assignors to Syncro Machine Company, Newark, N. J., a corporation of New Jersey

Application December 15, 1933, Serial No. 702,520

6 Claims. (Cl. 117—45)

This invention relates to improvements in automatic stopping devices for machines which apply to a longitudinally moving core, a web or strand of material in the form of a helical wrap comprising adjacent or overlapping turns.

An important object of the invention is to provide a machine in which the web or strand controls its operation in a manner so that in the event of breakage of the web or strand the entire machine will come to a stop.

The invention is broadly applicable to any machine for wrapping a web around a core. More particularly, it has been adapted for use on a machine of the type disclosed in our copending application, Serial No. 634,350, filed September 22, 1933.

There are many objects of this invention which will be more readily appreciated by a detailed reference to the attached drawings.

This invention resides substantially in the combination, construction, arrangement and relative location of parts all as will be set forth in full detail in the following specifications taken in connection with the attached drawings.

In the drawings:

Fig. 1 is a side elevational view of the mechanism of this invention showing some parts in cross sectional view.

Fig. 2 is a top plan view thereof.

Fig. 3 is a cross sectional view taken on the line 3—3 of Fig. 2.

Fig. 4 is a cross sectional view taken on the line 4—4 of Fig. 2.

Fig. 5 is an enlarged detail view showing the control or stopping switch in open position as distinguished from its closed position illustrated in Fig. 4.

Figs. 6 and 7 disclose a modified form of switch shown in closed and open position respectively.

Figs. 8 and 9 are plan and side views respectively of a further modified form of switch showing the switch in closed position.

Fig. 10 is a side view of switch in open position.

Figs. 11 and 12 are side and plan views, respectively, partly in cross section, of another modified form of switch shown in closed position.

Fig. 13 shows this switch in open position.

Figs. 14 and 15 are side views of a still further modification of the switch in closed and open positions, respectively.

Fig. 16 is a circuit diagram of the invention herein disclosed.

In machines for wrapping a web around a longitudinally advancing core, such as a wire in-

sulating machine, it is of considerable importance that the machine stop as quickly as possible upon the breakage of the web. The core or wire is advanced at a rapid rate and when the web breaks, it is apparent that a considerable length of wire may pass through the machine before it is brought to a stop. This means that the machine must either be run in the reverse direction so that the web can be applied from the point of breakage, or else the core must be cut out between the brake and the new point of application of the web, resulting in large wastage losses. Furthermore, in any event, the breakage of the web means stoppage of the machine, taking it out of productive use for considerable periods of time. Breakage often occurs in the web in machines of this type either both because of the nature of the web being applied or because the high rate of travel of the core or wire through the machine.

It is a purpose of this invention to provide a mechanism in which, immediately upon breakage of the web, the machine comes to an almost instantaneous stop. The control device of this invention for effecting stoppage of the machine consists of a switch controlled directly by the web itself. Thus, when the web breaks, the switch is operated to stop the machine.

Referring now to the drawings from which the details of the invention will be best understood, there is shown in Fig. 1 a portion of the supporting framework of the machine at 1. Extending horizontally from the machine frame is a bracket 2 which supports an electric motor 3 which drives the serving head. Supported on the upper end of the motor casing is a flanged plate 4 which is secured to the motor casing by the bolts 6. Extending upwardly so as to revolve on a vertical axis is the shaft 7 of the motor connected to the armature 5 thereof. Secured to this shaft is a suitably shaped collar 9 which is rotatably supported in the ball bearing structure 8.

Encircling the motor shaft, and secured to the collar 9 is the base plate 10 of the serving head which is secured to the collar by means of machine screws, as shown. Journalled for rotation upon the vertically extending end of the shaft 7 is a sleeve 11 which supports the spool or bobbin 15 of wrapping web or strand. Where wire is being wrapped, this web may be of some suitable insulating material.

Secured to the upper end of shaft 7 for rotation therewith is the nose piece 12. At 14 is the usual casing surrounding these parts.

Supported on the base plate 10 in balanced relation are a plurality of spindles 13 which rotatably support the guide sleeves 18. The spindles 13 are secured in the base plate by means of the nuts 17. The spindles 13 have longitudinal bores therethrough as clearly shown in Fig. 4. It might be noted that the motor shaft 7 likewise has a longitudinal bore therethrough through which the core to be wrapped advances longitudinally.

The upper end of spindle 13 is counterbored to receive a screw 20 which locks a collar 19 to the spindle. The screw 20 has a bore therethrough in which rests an insulating bushing 21 likewise centrally bored. Mounted in the bore of the bushing 21 is a contact 23 which is connected to a wire 30 extending through the spindle and the lower insulating bushing 22. Supported from the collar 19 is an arm 24 on which is pivotally supported at 25 a lever 26. Slidably mounted in one end of this lever is a contact 27 which cooperates with the contact 23 and which is resiliently urged into engagement with contact 23 by means of the flat spring 28. Secured to the other end of lever 26 is an arm 29. This arm 29 as will be noted from Fig. 4 extends at an angle to the longitudinal axis of lever 26. This angle should be at least approximately five degrees. In other words, the arm 29 projects generally along an axis below the horizontal axis of the lever 26 in its normal position. The free end of arm 29 is suitably shaped and positioned to be in the path of web 16 as it passes around the guide sleeve 18 and into the nose piece 12. Thus, the web engaging arm 29 from below holds contact 27 in engagement with contact 23. As will be described later, the machine is grounded and hence a circuit through the machine frame to the insulated contact 23 is completed when the machine is running properly and the web is unbroken.

The resilient connection between contact 27 and lever 26 does not interfere with this circuit even though there be a variation in the tension in web 16 and, hence, a variation in the pressure it exerts on arm 26. By this arrangement, the maintenance of this circuit is insured for any variations in the tension on web 16.

Immediately upon the breakage of web 16, lever 26 and arm 27 move to the position shown in Fig. 5 disengaging contacts 27 and 23. This breaks the circuits for the operating motors as will be described later, causing the stoppage of the machine. A very important feature of this structure is the position of arm 29 with respect to the axis of lever 26 in its circuit closing position. Since the serving head of a machine of this type may operate at speeds of from four thousand to five thousand revolutions per minute, it is apparent that the centrifugal forces involved are important. If the arm 23 is coincident with the axis of lever 26 or extends thereabove, the switch will not open upon the breakage of the web. However, with the structure as shown, if the web breaks, the centrifugal force acting upon arm 29 will aid the force of gravity in causing the arm to move downwardly into the position shown in Fig. 5. The parts are so proposed that when the machine is at a standstill, lever 26 will take the position shown in Fig. 5 if not held in place by the web. This tendency is enhanced and insures positive action when the serving head is rotating at high speeds through the action of centrifugal force in throwing arm 29 downwardly.

Wire 30 extends to a commutator ring 31

mounted upon a ring 32 of insulating material secured to the hub of the base plate 10. Engaging this ring (see Fig. 3) is a longitudinally sliding brush 35 mounted in a supporting sleeve or brush holder 34. The sleeve 34 is mounted in insulating supports 33—33 on the flanged plate 4. A spring 38 mounted in the sleeve 34 edges the brush 35 into contact with the commutator ring 31. At 36 is an insulating cap for holding the spring in place and allowing for adjustment of its pressure on the brush. The wire 37 is connected to the brush holder and forms part of the circuit controlled by the switch as will appear later.

The tendency of the machine to overrun even upon interruption of the driving motor circuits is eliminated by means of a brake band 39 which engages by its brake lining 40 the base plate 10.

As shown in Fig. 1, there is supported on the bracket 2 a solenoid winding 41 which is energized in cable 42. This solenoid has a magnetizable core 44 which controls an armature 45 pivotally supported at 46. Pivotally connected to the armature 45 at 48 is a vertically extending rod 47 which has mounted thereon a cam piece 53. This rod extends through a bracket 40 and is surrounded by a spring 50 which normally holds the parts in raised position as shown in Fig. 1. The cam piece 53 moves between the extending arms 51 of the brake band 39. A pin 52 extends through these arms and supports a pair of springs as shown in Fig. 2 which tend to draw the arms 51 together and hence tighten the brake band. When solenoid 41 is energized, however, the cam piece is pulled downwardly separating the arms 51 and releasing the brake.

The modified forms of stop switch structure will now be described. In the arrangement of Figs. 6 and 7 the pivot point 25^a for the lever 26^a is pivoted to one end. A spring 54 is employed to tend to cause the switch to open. In this case, the web 16 passes over the top of arm 29^a so that it will hold the switch closed against the action of spring 59 in normal operation. In this case, the axis of arm 29^a lies above the longitudinal axis of lever 26^a. Here again the requirement that this arm extend at an angle of at least approximately five degrees with the axis of lever 26^a holds. In this case, however, the angle is above the horizontal as distinguished from being below the horizontal in the form of switch shown in Fig. 4. Although the position of this structure is immaterial in the operation of the device, it might be noted that the preferred position would be at right angles to that shown in Figs. 6 and 7 in the plane of the paper in a manner similar to the arrangement shown in Fig. 4. This observation likewise applies to the other modifications to be described.

Figs. 8, 9 and 10 illustrate a modification particularly adapted for use with a web which is in the form of a thread or cord. In this case, the arm 26^b is pivotally mounted intermediate its ends in a manner similar to the structure of Fig. 4. However, the arm 29^b, instead of extending from the end of lever 26^b, is pivotally mounted on the arm 24^b below the pivot point 25^b. The lower end of lever 26^b is grooved so that arm 29^b may rest therein. In this case, the cord 16 passes up through the aperture in the enlarged end 29^b of lever 29^b. Fig. 10 shows the position of the parts in the event of the breakage of the cord.

The modification of Figs 11, 12 and 13 differs from the structures previously described in that the axis of the pivot 25^c is vertical instead of horizontal. In this case, the lever 26^c swings in a hori-

zontal plane and the contact 23^c in this form of structure is mounted in this case upon an L-shaped bracket 55 which is supported in the insulating bushing 21 and which is connected to wire 30. In this case, the web holds the switch closed and upon breakage the action of centrifugal force will cause the switch to open. The lever 26^c operating in a horizontal plane will be thrown open by centrifugal force even though the axis of the arm 29^c coincides with the axis of lever 26^c. In other words, the two axes do not need to lie at an angle.

The final modification is illustrated in Figs. 14 and 15. In this case, the contact 23^d is mounted upon a bracket 55^d so as to be supported above the contact 27^d. In this case, the web 16 bears on the under surface of arm 29^d and normally holds it in the position shown in Fig. 14. With this form of device, the axis of arm 29^d again extends at an angle and to one side of the axis of lever 26^d.

In all these forms of switches, it will be noted that contacts 23, 23^c and 23^d are insulated from the machine frame while contacts 21 and 22^d are connected directly to the machine frame which, as stated, is grounded. Likewise, the contacts 27 and 27^d are slidably mounted in their support so that the support may be free to move under varying conditions of operation produced by variations in the tension of the web without interfering with the circuit which includes these contacts. Likewise, this free movement of the support insures that the web will not be broken by reason of its engagement with the arms 29, 29^a, 29^b, 29^c and 29^d.

The complete power circuit for a machine of this type is illustrated in Fig. 16. The entire machine and its parts is fully set forth in our above-noted copending application. The machine comprises a capstan motor 75, a generator 67 directly connected thereto, one or more serving head motors 3, and a take-up reel motor 147. This motor is preferably a torque motor as illustrated in our copending application, Serial No. 694,944, filed Oct. 24, 1933. The main power supply circuit may be a three-phase alternating current circuit of suitable voltage. The supply wires are indicated at 60, 61 and 62. At 63 is the main switch which disconnects the major portion of the apparatus entirely from the current source. The leads 64, 65 and 66 from this switch are connected directly to the field of generator 67. These wires are likewise connected by wires 68, 69 and 70 to the fixed contacts of the main contactor 11. The field of motor 75 is connected by wires 72, 73 and 74 with the movable contacts of the main contactor 11. The wires 68 and 69 also connect one phase of the power source with the primary of the transformer 76. This transformer is for the purpose of supplying a lower voltage current for the control circuits. One terminal of the secondary of this transformer is connected by wire 77 to one terminal of each of the operating solenoids 78 and 79 of the main contactor 11 and the auxiliary contactor. The other terminals of these solenoids are connected by wire 80 to a normally closed switch 81. The other contact of this switch is connected by wire 82 to a terminal board.

Wire 77 is also connected by wire 83 to one terminal of the field 84 of a motor 85, the utility of which will later be described. The other terminal of the field 84 is connected by a wire 86 to one of the movable contacts of the auxiliary contactor. This wire 86 is also contacted by wire 88 to the normally open switch 87. The other terminal of this switch is connected by wire 89 to wire 85 which returns to the other terminal of the secondary of transformer 76 and also connects to the fixed con-

tact which cooperates with the movable contact connected to wire 86. At 90 and 91 are a pair of shading coils for the motor 85. These coils are connected together at one of the terminals of each. The coil 90 is connected by wire 92 to one contact of the single pole double-throw switch 104. Wire 96 connects wire 92 to wire 97 through normally closed contacts. The switch arm of switch 104 is connected by wire 98 to the other fixed contact of the auxiliary contactor. Its movable contact is connected by wire 97 to a point between the coils 90 and 91. The other terminal of the coil 91 is connected by wire 99 to the other fixed contact of switch 104.

At 93, 94 and 95 are rheostats, or adjustable resistances, which have one terminal of each connected together and to an adjustable contact arm. The other contact of each of these rheostats is connected by wires 101, 102 and 103, respectively, which lead to the armature of the motor 75.

As indicated by the dotted line 100, the motor 85^d operates the rheostats 93, 94 and 95. It likewise operates the switch 104 and the switches 81 and 81^d. Thus, in the normal position before starting, the rheostats 93, 94 and 95 are in a position so that their entire resistance is in the armature circuit. At that time, switch 81 is closed and switch 81^d is open. Switch 104 is in the position shown.

At 104^d is a four-pole double-throw reversing switch. The purpose of this switch is to reverse the current flow to the serving head motor to cause its operation either in forward or reverse. Wires 105 and 105^d extend to the reversing switch, as shown. Current flows from this circuit through wires 107 and 107^d to the field of motor 3. Wire 106 extends directly from the generator to the field. A similar circuit extends from the generator through wires 108 to 109, to the reversing switch 104^d. Current flows from the switch through wires 112 and 112^d to the armature of the serving head motor 3. The third wire of this circuit extends directly from the generator as indicated at 110. The contacts of the reversing switch are cross connected in the usual manner so that by properly positioning the switch the field and armature of the motor 3 may be energized to operate the motor in either direction.

The brake solenoid 41 is connected by wire 42 to one phase of the circuit on the output side of the main contactor, so that the closing of the main contactor energizes the brake coil to release the brake on the serving head. As soon as the main contactor opens coil 41 is de-energized and the brake applied.

The circuit for the stop switch will now be described. Current for this circuit is secured from the secondary of transformer 76. This circuit is preferably operated by a current of a voltage of approximately 24 volts. For this purpose, the secondary of the transformer is attached at the proper point and grounded by the wire 113. The other terminal for the circuit extends from wire 85 through wire 114 to a point between the signal lamps 115^a and 115. The other terminal of lamp 115 is connected through wire 116 and the relay wire 117 to wire 30 which terminates at the insulated contact 23 of the control switch. The frame of the machine is indicated as grounded by the wire 118. Wire 80 is connected through the normally opened switch 200 and a wire 121 to a fixed contact control by the contact disc 120. The other fixed contact controlled by this disc is connected by wire 119 to the terminal board. A second contact disc 122 controls a pair of contacts 75

one of which is grounded at 123. The other is connected by wire 124 to the other terminal of signal lamp 115a.

- The three terminals of the terminal board are connected to the start and stop switch. At this board wire 82 is connected to wire 125 which terminates at a fixed contact of the start switch 126. The other fixed contact is connected by wire 127 to wire 119 through the terminal board. Wire 85 is connected through the terminal board to wire 130 which extends to one fixed contact of the normally closed stop switch 129. The other contact is connected by wire 128 to one of the contacts of the start switch, as shown.
- 15 The take-up torque motor 147 is energized from the current source through wires 140, 141, and 142, switch 143, and wires 144, 145 and 146. The armature of this motor has connected therein through the circuit wires 148 the adjustable resistance combination 149. This combination includes three adjustable resistances which are manually operated by means of a single control handle as diagrammatically illustrated by the dotted line 150.
- 20 25 The necessary lamps and trouble lights, as well as the electric drier, are energized from a suitable current source connected to wires 151. The switch at 152 controls this circuit. The lamp 153 represents a trouble lamp and the lamp 154 represents a lamp which may be mounted adjacent the serving head. The electric heater 155 is energized from this circuit. This heater is likewise disclosed in our copending application first mentioned above. Its purpose is to dry the 30 insulating adhesive which is applied either under and/or over the web after it is applied to the core. In the circuit thereto is a thermostatic switch for turning the heater on or off within desired temperature limits. The heater comprises a plurality of resistances such as, for example, three resistances, controlled by a well-known form of switch indicated diagrammatically at 157. This is a four-position switch—in one position, one unit of the heater is in circuit; in the second position, two units are in circuit; in the third position, three units are in circuit and in the fourth and final position, all units are 35 out of circuit.
- 40 45 The operation of these circuits will now be described. To set the apparatus in operation, the main switch 63 is closed. As a result, current is fed to the fixed contacts of the main contactor 71 and to the field of generator 67. Likewise, the primary of transformer 76 is energized. At the same time, switch 104 is normally closed to a 50 position so that the serving head motor 3 will be prepared for energization for forward or normal drive.
- 55 60 As disclosed in our first mentioned copending application, by this arrangement, any movement of the serving head which is directly connected to motor 75 and the directly connected generator 67, will cause an equivalent and simultaneous movement of the serving head. This means, then, that any movement of the core will insure the application of the web thereto. At this time, with the machine at a standstill, all of the resistance of rheostats 93, 94 and 95 is in circuit 65 with the armature of motor 75. Likewise switch 81 is closed and switch 104 is in the position shown. Switch 87 is open—main contactor 71 is open—the auxiliary contactor 79 is open—and the winding of relay 117 is deenergized. With 70 winding 117 deenergized, contact disc 120 is out

of engagement with its contacts and contact disc 122 is in engagement with its contacts.

As will now be apparent, the stop switch is controlled by the web at a point between the web supply cop and the point of application of the web. Thus, when the web breaks, all circuits are opened and the serving head brake applied to bring the machine to an almost instantaneous stop. This reduces waste and eliminates the necessity of rewinding the core back to the break, 10 as distinguished from prior art practice in which a considerable amount of core passes through the machine after the web breaks before the machine stops.

To start the machine, start switch 126 is closed. Current then flows from one terminal of the secondary of transformer 76, through wire 77, relay winding 78, wire 80, normally closed switch 81, wire 82, wire 125, switch 126, wire 128, normally closed stop switch 129, wire 130, and wire 85, back to the other terminal of the secondary transformer 76. The energization of relay winding 78 causes the closing of the contacts operated thereby. The result is that current flows through wires 72, 73, and 74, to the field of motor 75 setting it in operation. This causes the operation of generator 67 and through its operation the operation of the serving head motor 3.

It should be noted that it is preferable that switch 143 be closed before the start switch 126 is closed. This energizes the take-up motor 147, causing the wire, as it comes from the capstan to the take-up reel, to be under a tension, depending upon the energization of the take-up motor. This motor being a torque motor, it will exert a constant pull on the wire, which pull may be manually adjusted by adjusting the resistance in the armature windings of the motor through the manual rheostat combination 149.

The energization of relay winding 78 also closes switch 200. The return circuit for the winding 78 is then through switch 200, wire 121, contact disc 120, wire 119, wire 127, wire 128, normally closed stop switch 129, wire 130, and wire 85 to the other terminal of the secondary of transformer 76. This provides a holding circuit for the relay winding 78 keeping the main contactor closed.

At the time of energization of relay winding 78 the relay winding 79 of the auxiliary contactor is energized. As a result, the circuits controlled thereby are closed. It should be noted that the holding circuit for the relay winding 78 just described also forms a holding circuit for the winding 79. The closing of the auxiliary contactor completes a circuit for the field 84 of motor 85 as follows: Current flows through wire 83, field winding 84, wire 86, left-hand contacts of the auxiliary contactor, wire 85 to the terminal of the secondary of the transformer 76. At the same time, the shading coil 91 is energized as follows: from the right-hand end thereof through wire 99, switch 104, wire 98, the right-hand contacts of the auxiliary contactor, and wire 97, back to the other terminal of this shading coil. As a result, motor 85 is set into operation. This motor causes the resistances of rheostats 93, 94 and 95 to be gradually cut out of the armature circuit of motor 75 as it comes up to speed. Likewise, as this motor starts to operate, normally closed switch 81 opens and normally opened switch 87 closes. As the resistances in the motor armature circuit are completely cut out, the switch 104 is swung from the position shown to engage left-hand contacts to set the motor for operation in the opposite

direction. This stops motor 85' by breaking the circuit for the shading coil 91. This motor and the parts controlled thereby are then set for reverse operation when the machine is brought 5 to a stop, at which time the resistances of the rheostats 93, 94 and 95 are cut back into the motor armature circuit.

Switch 104 is then set for reverse operation 10 completing the circuit for the shading coil 90 through the auxiliary contactor 79. As will be apparent, the circuit for the shading coil 90 will also be completed through the normally closed contact of the auxiliary contactor so that the motor 85' upon energization will be prepared to 15 cut all of the resistance back in the armature circuit of the motor 75 either while the machine is running or when it is deenergized.

Switch 104 is an adjustable limit switch and 20 may be manually set so as to control the amount of resistance cut out of the armature circuit and, hence, determine the speed of operation of the machine. In one extreme position of adjustment of switch 104 little or no resistance is 25 cut out so that the machine runs at slow speed. At the other limiting position of adjustment of this switch all of the resistance is cut out and the machine runs at maximum speed. By adjusting the limit switch 104 between these extremes, any desired speed of operation of the 30 machine is secured. As pointed out above, the motor 85' which operates the rheostats likewise operates the switch 104 and at the end of its movement in either direction sets this switch for the necessary operation in the reverse direction. The speed of the machine may be controlled 35 while running by energizing the motor 85' for reverse operation since the shading coil 90 is in closed circuit through the auxiliary contactor 79 when it is either energized or de-energized. Thus, if switch 104 is at its left-hand position the 40 shading coil circuit is complete.

A circuit for the automatic stop switch is completed as follows: from one terminal of the secondary of transformer 16 through wire 85, wire 45 114, signal lamp 115, wire 116, relay winding 117, wire 30, contact 23, contact 27, frame of the machine to ground at 118, and thence back through ground 113 to the secondary of the transformer. It will be apparent that this circuit is complete 50 the moment main switch 63 is closed which results in the energization of the transformer 16. This is necessary in order that contact disc 120 and contact disc 122 be in the position shown 55 in the drawings. Signal lamp 115 may preferably be a green lamp indicating that, so far as the web control is concerned, things are normal.

If the web breaks, the circuit for 117 is broken at contacts 23 and 27. Contact disc 120 disengages its contacts and contact disc 122 engages 60 its contacts. The result is that signal lamp 115 is energized through wire 124. This lamp may be a red lamp indicating the fact that the web is broken. The disengagement of contact disc 120 65 from its contacts, breaks the holding circuit for the relay winding 18 causing the main contactor to open, with the result that the machine comes to a stop. It will be noted, however, that the field of generator 67 is maintained energized, with the result that as it slows down to a stop, 70 motor 3 will be driven in timed relation therewith so that the web will be properly wrapped on the core up to the instant of complete standstill.

At the same time, the circuit for the shading 75 coil 90 will be completed because the auxiliary

contactor moves to open position simultaneously with the opening of the main contactor. The result is that the contact through wire 96 is closed so that the shading coil 90 will have its circuit completed as follows: from the right-hand end thereof through wire 97, wire 96 including the contact therein, wire 92 to the other terminal of the shading coil 90. At this time, the field 84 of the motor is energized through wire 87, field 84, wire 86, wire 88, switch 87 which is now 10 closed, wire 89 and wire 85, back to the other terminal of the secondary transformer 16. Thus, motor 85' is energized in the reverse direction so that the resistances in the armature circuit of motor 75 are gradually fully cut into circuit. 15 As the motor arrives at the end of its reverse stroke, switch 87 is open and switch 81 is closed. Likewise, switch 104 is moved back to the position shown in the drawings.

Similar action occurs to stop the machine by 20 opening normally closed stop switch 129. When this switch is open, assuming the apparatus running normally, the holding circuit for relay winding 18 is broken, with the result that the main contactor opens, as well as the auxiliary contactor. 25

The previous description of the trouble light circuit and the heating circuit fully sets forth the nature and operation of this apparatus. To 30 fully deenergize the entire apparatus, switch 143 and switch 63 may then be opened.

From the above description, it will be apparent that this invention resides in certain principles of construction and operation which may be embodied in other forms and carried out in other ways without departure from the scope thereof. We do not, therefore, desire to be strictly limited to the disclosure as given for purposes of illustration, but rather to the scope of the appended 35 claims.

What we seek to secure by United States Letters Patent is:

1. A web feeding combination comprising a motor, a generator connected thereto, circuits for energizing said motor, a main contactor in said 45 circuits for controlling said motor, a serving head motor, circuits for energizing the serving head motor from said generator, circuits for controlling the main contactor including start and stop switches, a holding circuit for the main contactor, an electro-magnetically operated switch in said holding circuit, a web serving head operated by the serving head motor and a centrifugally operated switch for controlling the electromagnetically operated switch, said centrifugally operated switch being held against operation by the web.

2. A web feeding combination comprising a web serving head, a serving head motor, a motor-generator, circuits for energizing the motor-generator including an electro-magnetically operated main contactor, connections for energizing the serving head motor from the generator, circuits including a start and stop switch for controlling the main contactor, a holding circuit for 60 the main contactor, a relay switch in the holding circuit, and a control circuit for the relay switch including a switch mounted on the serving head and normally held closed by the web.

3. A web feeding combination comprising a web 65 serving head, a serving head motor, a motor-generator, circuits for energizing the motor-generator including an electro-magnetically operated main contactor, connections for energizing the serving head motor from the generator, re- 70

- versing switches in said connection for operating the serving head motion in either direction, circuits including a start and stop switch for controlling the main contactor, a holding circuit for the main contactor, a relay switch in the holding circuit and a control circuit for the relay switch including a switch mounted on the serving head and normally held closed by the web.
4. A web feeding combination comprising a web serving head, a serving head motor, a motor-generator, circuits for energizing the motor-generator including an electro-magnetically operated main contactor, connections for energizing the serving head motor from the generator, circuits including a start and stop switch for controlling the main contactor, a holding circuit for the main contactor, a relay switch in the holding circuit, a control circuit for the relay switch including a switch mounted on the serving head and normally held closed by the web, an auxiliary contactor in circuit with the main contactor and its holding circuit, a motor operated rheostat connected to the motor of the motor-generator and circuits for the rheostat motor including the auxiliary contactor.

5. In a flyer for machines of the type described, a rotatable support, a cop spindle journaled on said support for rotatably mounting a cop, a guide post secured to said support around which the web passes from the cop, a fixed contact mounted on and insulated from the post, a switch arm pivotally mounted on the post, an extension on said arm positioned to engage the web; a motor for operating the support, and means interconnecting said contact, switch arm and motor for stopping the motor when the switch arm is released by breakage of the web. 10

6. In a machine of the type described, the combination comprising a serving head for feeding a web, a brake band engageable with the serving head, spring means for normally holding the brake band in engagement with the serving head, means for disengaging the brake band from the serving head, electro-magnetic means normally energized when the serving head is in operation 15 for moving said means to disengage the brake band and means for deenergizing the electro-magnetic means when the web breaks. 20
